FERNANDO LOPEZ CERVERA, OF TACUBA, MEXICO.

WATER-CRAFT-PROPELLING MECHANISM.

Application filed August 6, 1925. Serial No. 48,520.

To all whom it may concern:

Be it known that I, FERNANDO LOPEZ CERVERA, a citizen of the United States of Mexico, residing at Tacuba, Distrito Federal, Mexico, have invented certain new and useful Improvements in Water-Craft-Propelling Mechanism, of which the following is a specification.

This invention relates to new and useful improvements in water craft propelling mechanism.

The primary object of the invention is to provide a mechanism by means of which a rowboat, or the like, may be manually propelled while the operator of the mechanism is facing toward the front or bow of the boat, whereby greater safety is insured by enabling the craft to be more accurately steered.

A further object of the invention is to provide a mounting for the above referred to propelling mechanism which will do away with the risk of losing an oar encountered by persons using ordinary oars having removable oar locks.

A still further object of the invention is to provide a propelling mechanism which may be folded against the inner side of a gunwale when not in use.

Other objects and advantages of the invention will be apparent during the course of the following description.

In the accompanying drawing forming a part of this specification and in which like numerals are employed to designate like parts throughout the same,

Figure 1 is a fragmentary side elevational view of the craft propelling mechanism embodying this invention and shown properly mounted upon a gunwale of a rowboat, or the like.

Figure 2 is a top plan view of the mechanism shown in Fig. 1 and is intended to illustrate the range of movement of the handle and blade portions of the propelling mechanism.

Figure 3 is a side elevational view of a gunwale with the mechanism shown in Fig. 1 folded into an inoperative position against the inner side of the said gunwale, and

Figure 4 is a top plan view of the mechanism shown in Fig. 1 with a top housing plate removed.

In the drawing, wherein for the purpose of illustration is shown a preferred embodiment of this invention, the numeral 5 desi-

nates the gunwale of a rowboat, or the like, upon the upper face of which is mounted a bracket 6 having the upstanding, spaced, apertured ears 7 through the apertures of which extends a rod 8. Pivotaly mounted upon this rod 8 are the arcuate arms 9 which are connected at their outer ends by the spindle shaft 10.

This spindle shaft has mounted thereon a two-part bearing 11 which is permitted to rotate in respect to the shaft and is suitably fastened to the under face of the lower plate 12 which forms with the upper plate 13 a housing. The lower plate 12 is formed with diametrically opposed, upstanding bosses 14 to which the upper plate 13 is secured by means of the screws 15.

It will be noted, by inspecting Figs. 2 to 4 inclusive, that the plates 12 and 13 are of elongated formation and have passing through suitable apertures formed therein the spaced shafts 16 which extend below the bottom plate 12 and are connected at their lower ends by the arcuate arm 17.

As best shown in Figs. 1, 2 and 4, the portions of the shaft 16 located between the plates 12 and 13 have rotatably mounted thereon the toothed sectors 18 and 19 which have their teeth constantly meshing with each other. Extending radially from the sector 18 is a socket 20 which is intended to receive the shank portion 21 of a handle 22 which, for convenience, will be termed an oar handle portion. The toothed sector 19 is also provided with a radially extending socket 23 which is intended to receive the shank portion 24 of a blade 25 which will be termed the oar blade portion.

Rotatably mounted upon the portions of the shaft 16 extending between the ends of the arm 17 and the lower plate 12 are the supporting arms 26 and 27 which have connections 28 and 29 respectively with the sockets 20 and 23. The outer end of the supporting bracket 26 is provided with a ring portion 30 through which the shank portion 21 of the oar handle 22 extends. This ring 30 is provided with a set screw 31 by means of which the oar handle portion 22 may be held against longitudinal movement to permit the shank 21 to be adjustably received within the socket 20. The remaining supporting arm 27 is also provided at its outer end with a ring 32 through which extends the shank portion 24 of the oar blade part 25. The set screw 33 carried by the ring 32

is intended to function in the same manner as the set screw 31, i. e., to permit the shank 24 to be adjustably received and held within the socket 23.

- 5 To reduce friction as much as possible between the relatively movable portions of this propelling mechanism, the sectors 18 and 19 are provided with anti-friction rollers 34 while the opposite faces of the socket 10 portions 20 and 23 are provided with balls 35 which are received in suitable depressions formed in the said shanks and bear against the plates 12 and 13. The thrust bearings 36 are provided between the lower 15 faces of the journaled ends of the supporting arms 26 and 27 and the opposite ends of the connecting arm 17 to overcome friction between these relatively movable portions.

In Fig. 2 the paths through which the 20 handle and blade portions of the propelling mechanism move are intended to be outlined by the dotted lines. It will be understood that when the handle portion 22 moves toward the dotted line —a—, the oar blade 25 portion 25 will move toward the dotted line —b— while movement of the handle portion 22 toward the dotted line —c— will cause the blade portion 25 to move toward the dotted line —d—. These relative movements of the parts 22 and 25 are exactly opposite to the relative movements of the handle and blade portions of an ordinary oar and will thereby permit the operator of a pair of these oars 35 or propelling mechanisms to face toward the front or bow of a boat while propelling the same. To permit the handle and blade portions 22 and 25 to be arranged at suitable angles in respect to the gunwale 5 for causing the blade portion 25 to dip into and be withdrawn from the water surrounding the 40 craft equipped with this improved propelling mechanism, the housing and its supported element may be rocked or rotated 45 upon the shaft 10.

It will be noted that this improved form of propelling mechanism can hardly be lost overboard as often happens with ordinary oars, using removable oar locks. To overcome the disadvantage of being unable to "ship" the propelling mechanism, the pivotal mounting of the arcuate arms 9 upon the rod 8 will permit the entire mechanism to be swung into the position shown in Fig. 50 3 with the handle and blade portion extending in parallelism from one side of the housing formed by the plates 12 and 13. To pre-

vent movement of the handle portion 22 which would cause the blade portion 25 to move vertically above the gunwale 5, a supporting hook 37 is provided and is intended to receive the handle portion 22, as illustrated in Fig. 3.

It is to be understood that the form of this invention herewith shown and described is to be taken as a preferred example of the same, and that various changes in the shape, size, and arrangement of parts may be resorted to without departing from the spirit of the invention or the scope of the subjoined claims.

Having thus described the invention, I claim:

1. In a propelling mechanism of the type described, a housing supported to pivot on a horizontal axis, a pair of spaced shafts extending through said housing to depend therebelow, meshing toothed sectors rotatably mounted upon said shafts, a socket projecting radially from each of said sectors, a handle having a shank received in one of said sockets, a blade having a shank received in the other of said sockets, and means pivotally carried by the depending portion of said shafts connected to the shanks outwardly of the socket for adjustably holding said shanks in said sockets.

2. In propelling mechanism of the type described, the combination with a gunwale, of a pair of parallel arms pivotally connected at their inner ends to said gunwale, a shaft connecting the outer ends of said arms, a bearing rotatably mounted upon said shaft, a housing including spaced, parallel plates connected to said bearing, a pair of spaced shafts extending in parallelism through the plates of said housing, a pair of meshing toothed sectors mounted upon said shafts between said plates, a radially projecting socket carried by each sector, an oar handle having a shank received within one of said sockets, an oar blade having a shank received within the other of said sockets, supporting arms pivotally connected to said spaced shafts below the bottom plate of said housing, and means carried by the outer ends of said supporting arms for connection with said oar handle and blade for preventing the shanks of the same from being withdrawn from said sockets.

In testimony whereof I hereunto affix my signature.

FERNANDO L. CERVERA.
